UNITED STATES PATENT OFFICE.

LEWIS E. WATERMAN AND HARRY R. TRAPHAGEN, OF ROCKFORD, ILLINOIS,
ASSIGNORS TO EMERSON-BRANTINGHAM COMPANY, OF ROCKFORD, ILLINOIS,
A CORPORATION OF ILLINOIS.

DESIGN FOR A TRACTOR-BODY.

48,017.

Specification for Design.

Patented Oct. 19, 1915.

Application filed April 23, 1915. Serial No. 23,536. Term of patent 14 years.

To all whom it may concern:

Be it known that we, LEWIS E. WATERMAN and HARRY R. TRAPHAGEN, citizens of the United States, residing at Rockford, in the county of Winnebago and State of Illinois, have invented a new, original, and ornamental Design for Tractor-Bodies, of which the following is a specification, reference being had to the accompanying drawing, forming part thereof.

In the drawing, Figure 1 is a perspective

view of a tractor body, showing our new design; and Fig. 2 is a plan view of the same.

We claim:

The ornamental design for a tractor body, as shown.

LEWIS E. WATERMAN.
HARRY R. TRAPHAGEN.
